MULTI-CELL CARTONS

Charles W. Rosenburg, Jr., Buffalo, N.Y., assignor to F. N. Burt Company, Inc., Buffalo, N.Y., a corporation of Delaware

Filed Jan. 15, 1964, Ser. No. 337,765

7 Claims. (Cl. 229—28)

This invention relates to containers or receptacles and more particularly to partitioned multi-cell boxes or cartons which may be shipped and handled in flat collapsed condition or erected to parallelepiped configuration for use.

The general object of the invention is to provide a novel and improved carton of the class described which is of simple and economical one piece construction with partition and side wall panels folded from a single blank, the adjacent panels being hingedly secured together to provide a box for an unusually large number of cells disposed in alignment.

There exist some two and three cell cartons made from a single unitary blank with the cells disposed in a straight line, and some non-collapsible boxes having six and eight cells or even more, arranged in multiple alignment series, but the present invention provides a novel blank and carton formed therefrom which, by an ingenious arrangement of partitions and glued connecting or "stretch" panels, provides for four internal cells in a package which will retain its firm rectangular configuration when filled, but which can be collapsed empty to a flat condition permitting ready storage and transport with minimum required volume.

Other objects and features of novelty will be apparent from the following specification when read in connection with the accompanying drawings in which one embodiment of the invention is illustrated by way of example.

In the drawings:

FIGURE 1 is a view in perspective of a multi-cell box or carton embodying the principles of the invention, the top closure flaps of the carton being open to disclose the upper portions of the partition structure;

FIGURE 2 is a horizontal sectional view of the box taken along line 2—2 of FIGURE 1;

FIGURE 3 is a vertical sectional view taken on line 3—3 of FIGURE 2;

FIGURE 4 is a vertical transverse sectional view taken on line 4—4 of FIGURE 2;

FIGURE 5 is a plan view of a blank from which the novel carton may be formed;

FIGURE 6 is a plan view of the carton in collapsed condition as for packing, storing, or shipping; and

FIGURE 7 is a somewhat diagrammatic end view of the carton as it approaches collapsed condition.

Probably the best way to approach the disclosure of the invention is by way of the blank illustrated in FIGURE 5 of the drawings. The flat blank usually made of cardboard but which can be made of any similar relatively stiff material, is of unitary construction, only one piece being required to form all of the parts of the collapsed box or carton.

The carton is of rectangular cross-section and comprises side walls A, B, C, and D, side walls A and C adapted to be disposed opposite to each other and being of the same size and shape. End walls B and D are similarly disposed in opposite positions and are of corresponding dimensions.

Hingedly connected at the upper portion of the side wall panel A, as by means of the score line a_1 , is the lid or cover panel A_1 , which itself has a tab A_3 hingedly connected thereto by the score line a_3 . The side wall panel

2

A also has a bottom flap A_2 connected thereto along the score line a_2 .

End wall panel B has a flap B_1 hingedly connected thereto along its upper edge by means of the score line b_1 , and is similarly provided with a bottom flap B_2 connected thereto by means of the score line b_2 .

The opposite side panel C does not have an upper flap but is provided with a notch c_1 which is adjacent the point where the closure tab A_3 is inserted, and aids in the removal of this tab when the carton is to be opened, as will presently be described.

A bottom flap C_2 is hingedly connected to the side wall panel C along the score line c_2 . End panel D with its upper and lower flaps D_1 and D_2 hingedly connected along the score line d_1 and d_2 is virtually the mirror image of end panel B with its flaps.

Now, in order to provide partitions for dividing the carton into the desired four cells, certain partition panels and connecting and securing panels (which latter may be termed "stretch" panels) are provided all integrally connected serially with one or the other end margins of the end wall panels A and D. For example, hingedly secured by means of the score line e to the left-hand edge of panel A is a stretch panel 1. A partition panel 2 is hinged to the stretch panel 1 along the score line f . Similarly a stretch panel 3 connects the partition panel 2 and a partition panel 4, being respectively hinged thereto along the score lines g and h . Then a final securing or stretch panel 5 is provided which is hinged to the partition panel 4 along the score line i . This series is designated II in the drawings.

At the opposite end of the basic side wall portion of the unitary blank, a stretch panel 6 is hingedly connected to the right-hand edge of the wall panel D along the score line j . A partition panel 7 connects the stretch panel 6 with a further securing or stretch panel 8, being respectively connected thereto along the score lines k and l , making series I.

A notch 15 is cut in the upper edges of the panels 2, 3 and 4, this arrangement providing a bevelled edge 16 at the upper portion of the wall panel 2, an abbreviated upper portion of the stretch panel 3, and a partial abbreviated portion of the partial panel 4 with an inclined edge 17 complementary to the edge 16. The upper portion of the panels 7 and 8 are also notched out as at 18, an inclined edge 19 being provided in the upper part of the partition 7, all of this for purposes to be described presently.

The completely erected collapsible partitioned container formed from the blank shown in FIGURE 5 is designated by the general reference numeral 10 and is shown in a perspective view from above the container in FIGURE 1 of the drawings.

The procedure in securing the various panels together to form the box will now be described. Although the sequence of bending, folding, and gluing may be varied as desired, one preferred way of bringing the parts into proper position and securing them would be as follows: the first stretch panel extending from the wall D is bent at right angles to that wall and then the partition panel 7 is again bent at right angles to the panel 6 but parallel to the wall D. The terminal securing stretch panel 8 is then glued to the rear face of the front wall panel C.

Next, the stretch panel 1 is folded all the way over through an angle of 180° to contact about one-half of the inner surface of the side wall panel A. The central partition panel 2 is swung to a position where it stands at a right angle to both the wall panel A and the stretch panel 1 and so as to be disposed in parallel relationship with the partition panel 7 and end panel D. The stretch panel 3 is then placed in contact with the inner face of the wall C and adhesively secured thereto in such a

way that the partition panels 2 and 4 are disposed in parallel relationship with each other and with the end walls B and D.

The final stretch panel or securing panel is then tucked to a certain distance beneath the initial stretch panel 1 and the panels 5 and 1 are appropriately adhesively secured to each other and to the inner surface of the wall panel A. This is all graphically shown in the sectional view comprising FIGURE 2 of the drawings and, of course, supplemented by the sectional views of FIGURES 3 and 4. When thus assembled and secured, the carton is susceptible of being collapsed in either direction to a flat laminar condition. When collapsed in one direction the partition will occupy the position shown in FIGURE 6 of the drawings and it is easy to visualize that collapsing the carton in the opposite direction will yield a plan view which would be a mirror image of FIGURE 6.

In order to erect the carton to position for the reception of articles within the cells provided therein, the bottom flaps B₂ and D₂ of the end wall panels are folded inwardly and then the flaps A₂ and C₂ folded together and secured in any suitable manner, as by gluing, as will be perceived from the showing at the bottoms of FIGURES 3 and 4.

It is obvious that in order to close the top of the carton the upper end flaps B₁ and D₁ are folded inwardly and the cover panel A₁ swung over on top of them with the closure tab A₃ inserted behind the notched upper portion of the front wall C and overlying the ends of the partitions 2 and 7 in the space provided by the curtained portions 16 and 19 thereof.

The provision of the notches 15 and 18 serve the purposes of cutting back the partitions 4, 2 and 7, not only for the purpose of permitting the tab A₃ coming to its terminal closed position, but also for assisting in the removal of articles from the four cells provided by the partitions. For example, suppose that the carton is to contain four boxes of photographic film. The cut-away portions at 17, 16 and 19 permit entry of the thumb and fingers to grasp the boxes and remove them from the carton.

For initial shipment or storage of the cartons, or for handling the cartons for re-use, they may be collapsed readily, for example, to the condition shown in FIGURES 6 and 7 of the drawings where they occupy a minimum of space.

It is understood that various changes and modifications may be made in the embodiment illustrated and described herein without departing from the scope of the invention as defined by the following claims.

Having thus described the invention, what is claimed as new and desired to be secured by Letters Patent is:

1. A one-piece multi-cell carton comprising pairs of respectively oppositely disposed side and end wall panels, hingedly connected at adjoining side edges to complete a rectangular structure; certain of said side and end wall panels provided at their upper and lower edges with hingedly connected cooperating top and bottom forming flaps; two series of unitary hingedly connected stretch panels and partition panels integral with and hinged to the respective meeting side edges of the adjoining terminal side and end panels, and directed inwardly of the carton, each series comprising alternate stretch and partition panels beginning with a stretch panel secured flatwise to the adjacent side wall panel, the initial stretch panel of the first of said series being of the width of the first cell at that end of the carton and the initial stretch panel of the second series being of a width equal to the combined width of said first cell and the second cell in the series, the partition panels being of a length equal to that of the end wall panels, the second stretch panel of said first series being of multi-cell width and the second stretch panel of said second series being of single cell width.

2. The multi-cell carton as set forth in claim 1 in

which the initial stretch panel of said second series is folded through an angle at 180° and secured directly face to face to the inward surface of the side panel to which it is hinged, the next partition panel of the second series 5 extending across the carton and defining the extent of the second cell for said terminal end panel; the initial stretch panel of the first series bent at an angle of 90° with respect to the end wall panel from which it extends and secured face to face to the inward surface of the longer initial stretch panel of the second series, the next partition panel of the first series extending across the carton and defining the extent of the first cell; the second stretch panel of said first series extending along and secured to the inward surface of the opposite side wall panel; the second stretch panel of said second series extending along and secured to the inward surface of the longer second stretch panel of said first series, and a second partition panel extending from said second stretch panel of the second series extending across the carton 10 to define the extent of the third cell.

3. The multi-cell carton as set forth in claim 2 in which there is provided a third stretch panel hinged to and extending at right angles to said second partition panel of the second series back toward the first-named end of the carton and extending alongside of and secured to the inward surface of said first-named side wall panel and tucked behind at least a portion of the first stretch panel 15 of the second series.

4. A one-piece multi-cell carton comprising pairs of respectively oppositely disposed side and end wall panels, hingedly connected at adjoining side edges to complete a rectangular structure, certain of said side and end wall panels provided at their upper and lower edges with hingedly connected cooperating top and bottom forming flaps, 25 two series of unitary hingedly connected stretch panels and partition panels integral with and hinged to the respective meeting side edges of the adjoining terminal side and end panels and directed inwardly of the carton, each series comprising alternate stretch and partition panels 30 beginning with a stretch panel secured flatwise to the adjacent side wall panel, said stretch panels being either of once or twice the width of the cells between partition walls in the carton, whereby the disposal of the partition panels will be at equal distances apart and from the end panels.

5. A one-piece blank for the production of a multi-cell carton which blank comprises a series of wall panels consisting, in the named sequence, of a first side wall panel, a first end wall panel, a second side wall panel, and a second end wall panel; a first series of cell-forming panels hinged to and extending from said second end wall panel and consisting, in the named sequence, of a stretch panel, a partition panel, and a second stretch panel; and a second series of cell-forming panels hinged to and extending from said first side wall panel and consisting, in the named sequence, of a stretch panel, a partition panel, a second stretch panel, and a second partition panel.

6. A one-piece blank for the production of a multi-cell carton which blank comprises a series of wall panels consisting, in the named sequence, of a first side wall panel, a first end wall panel, a second side wall panel, and a second end wall panel; a first series of cell-forming panels hinged to and extending from said second end wall panel and consisting, in the named sequence, of a stretch panel of a width equal to that of a first cell of the carton, a partition panel, and a second stretch panel of a width equal to that of the first and second cells; and a second series of cell-forming panels hinged to and extending from said first side wall panel and consisting, in the named sequence, of a stretch panel of a width equal to that of the said first and second cells, a partition panel, a second stretch panel of the width equal to that of said second cell, and a second partition panel, and a third

stretch panel of a width sufficient to provide terminal securement to the adjacent side wall.

7. A one-piece multi-cell carton comprising pairs of respectively oppositely disposed side and end wall panels, hingedly connected at adjoining side edges to complete a rectangular structure, certain of said side and end wall panels provided at their upper and lower edges with hingedly connected cooperating top and bottom forming flaps, two series of unitary hingedly connected stretch panels and partition panels integral with and hinged to the respective meeting side edges of the adjoining terminal side and end panels, and directed inwardly of the carton, each series comprising alternate stretch and partition panels beginning with a stretch panel secured flatwise to the adjacent side wall panel, said stretch panels being either of once or twice the width of the cells between partition walls in the carton, whereby the disposal of the partition panels will be at equal distances apart and from the end panels, and notches formed in the upper edges of certain

of said partition panels adjacent one of said side walls affording grasping access for the fingers in removing articles from the cells, all junctions between wall panels and partitions being hinge connections whereby the carton 5 may be readily collapsed to flat condition.
